Hadley K. Burch, Ridgebury Road, R.D. 1, Danbury, Conn., and Malcolm K. Parkhurst, 142 E. 150th St., New York, N.Y.

Filed July 5, 1960, Ser. No. 40,845
10 Claims. (Cl. 200—67)

This invention relates to snap-acting devices, and in particular to snap-acting devices of the over centering kind which are particularly adapted for miniaturized versions of snap-acting switches.

It is well known that snap-acting devices may be made in the form of multi-legged members, with the stressing of one or more of said members creating internal stresses which result in imparting a generally dished shape to the member, with the result that when mechanically further stressed, the device will change shape or dish suddenly. While satisfactory for many uses and achieving a large measure of commercial success, such devices, when made in very small sizes, may become difficult to use, because of inherent criticality to dimensional tolerances. Also, when such devices are reduced to relatively small sizes, the amount of snap motion may not be very large. Thus, electrical snap-switches using such devices may not be entirely suitable for certain applications, in view of the resulting very small contact opening.

It is a general object of the present invention, therefore, to provide a new and improved snap-acting device, readily adaptable as an electrical snap-switch or the mechanical motivating part of some other device.

Another object of the invention is to provide a new and improved snap-acting device especially adapted to the production of exceptionally small snap-switches.

It is a further object of this invention to provide a snap-acting device which has a relatively large amount of snap-motion for its size.

A further object of this invention is the provision of a snap-acting device which for its size is relatively insensitive to dimensional tolerances, thus leading to ease of manufacture.

Yet another object of this invention is to provide a snap-acting electrical switch of miniature size which is relatively simple to manufacture, and simple to calibrate.

Other objects and advantages will be in part obvious and in part pointed out hereinafter.

The invention accordingly comprises the elements and combinations of elements, features of construction, and arrangement of parts which will be exemplified in the structures hereinafter described, and the scope of the application of which will be indicated in the following claims.

Briefly stated, a snap-acting mechanism in accordance with the present invention comprises a blade of a flat, resilient material having outer and center legs extending in essentially the same direction from a juncture portion. The free ends of the outer legs are connected to a support by a pair of connections which are spaced so as to distort the outer legs toward one another, thus urging the center leg toward a position of relative equilibrium. One of the connections permits pivotal movement of its corresponding leg, and means are provided for imparting pivotal movement to that leg so as to carry the center leg away from the aforesaid equilibrium position.

In the accompanying drawings, in which several of various embodiments of the invention are illustrated:

FIG. 1 is a plan view of a switch of this invention;

FIG. 2 is a plan view similar to FIG. 1 but with certain parts removed, to assist in seeing other structure;

FIG. 3 is a front view of a switch incorporating the FIG. 1 structure and also a casing or cover, and actuating

2

means, parts of the casing being broken away to reveal details of structure;

FIG. 4 is a side-elevation of the FIG. 3 structure, again with parts of the casing broken away to reveal details of structure;

FIG. 5 is a bottom view of the FIG. 1 structure;

FIG. 6 is an enlarged view of an unstressed snap-acting blade used in the FIG. 1 structure;

FIG. 7 is an enlarged isometric view of an actuating arm used in the FIG. 1 embodiment;

FIG. 8 is a greatly enlarged fragmentary plan view of a portion of a mounting pin, the aforesaid actuating-arm, and snap-acting blade;

FIG. 9 is an enlarged view of a portion of the FIG. 3 structure (with some parts omitted for clarity) to illustrate the parts in one operating position;

FIG. 10 is a cross-section of the FIG. 9 device, taken in the direction of sight lines 10—10 thereon;

FIG. 11 is a view similar to FIG. 9, but showing the same parts in a second position;

FIG. 12 is a cross-section of the FIG. 11 device, taken in the direction of sight lines 12—12 thereon;

FIG. 13 is a view similar to FIG. 1, but showing a second embodiment of the invention;

FIG. 14 is a front view of the FIG. 13 embodiment; and

FIG. 15 is a simplified representation of a switch in accordance with another embodiment of the invention.

Similar reference characters indicate corresponding parts throughout the several views of the drawings.

In carrying out this invention, use is made of an element shown and described in United States Letters Patent No. 2,777,032, issued January 8, 1957, to which attention is directed for a full disclosure of its construction. For the purpose of this application, it will be sufficient to describe the said element or blade briefly as follows.

Turning to FIG. 6 of the drawings, the element or blade is indicated generally by numeral 2, and consists of a three-legged member having the outer legs 4 and 6 and the inner or middle leg 8. The outer legs 4 and 6 are joined to the middle leg 8 by means of the curved juncture portions 10 and 12. Openings are provided in the end of each of the outer legs 4 and 6. In the example shown, such openings are the mounting holes 14 and 16. Instead of holes, slots could be provided extending inwardly of each end from the outer edge thereof, since it is not necessary that there be a complete enclosure at the end of each arm. What is needed for this embodiment is that there be bearing rims lying within the confines of said ends. The middle leg 8 carries on its free end opposed contacts 18 and 20 which are electrically connected to the middle leg. The blade is made as an integral unit by stamping it out of sheet Phosphor bronze, beryllium copper, or other electrically conductive spring material. Contacts 18 and 20 may be attached to leg 8 by riveting or welding, using well-known techniques.

As explained in the aforementioned patent, the blade is stressed to make it snap-acting by mounting the blade in such a manner that the ends of legs 4 and 6 are forced toward each other. This causes the blade to adopt a "dished" configuration, with the end of center leg 8 being moved out of the plane of the ends of legs 4 and 6. If the center arm is now pushed toward the plane of the outer legs, a position of instability will be reached, and further motion of the center leg in the same direction will cause the blade to change its direction of "dishing" with a snap-action, thus throwing the end of leg 8 to the other side of the blade with a snap-action. Utilizing the present invention, a snap-switch can be made in miniature size, and at present such devices are being constructed in which the blade shown in FIG. 6 is made of 0.004 inch thick

beryllium copper, and is 0.192 inch long, and 0.208 inch wide.

Referring now to FIGS. 1, 3 and 4 there is shown (enlarged by a ratio of approximately 15:1) a plan view of a miniature switch incorporating the FIG. 6 blade. (In this drawing, as in others, certain thicknesses of materials and other dimensions are not scaled in proportion, the reason being the shading and other requirements of Patent Office drawings.) A base is provided comprising the metal ring 22 in which is fused the glass filler or electrically insulating header 24, terminals 26, 28 and 30 of electrically conducting metal passing through the glass and being fused thereto while being insulated from each other. The construction of the header plate and its terminals follows conventional practice, and is not a part of this invention.

As indicated above, terminal 26 extends through the header, and on its inner end is provided the enlarged shoulder or flange 32 and a neck 34. A switch support plate 36 of metal is provided and has therein a mounting hole 38 which is a squeeze fit onto neck 34, as shown. (If desired, support plate 36 may be welded to shoulder 32). Support plate 36 is provided with two other holes 40 and 42, as shown. A post 44 is provided which has at one end the reduced end portion 46 which is press-fitted into hole 40. Post 44 is made of metal and is hexagonal in cross-section to enable gripping it with a wrench for turning.

The other end of post 44 is provided with the neck portion 48. A flat-bottomed circular groove 50 is provided, as shown, at the junction of neck 48 with body 44, and the body 44 is chamfered or relieved as shown at 52. Similarly the neck 48 is relieved by chamfer 54 on the other side of groove 50.

Another post 56 is provided with a reduced end portion 58 which is squeeze-fitted into hole 42 in plate support 36. Similarly to post 44, post 56 is provided with a neck portion 60, and a flat-bottomed groove 62 like groove 50. Post 56 is relieved by the chamfers 64 and 66, similar to chamfers 52 and 54.

Neck 48 is formed on post 44 off-set from reduced portion 46. That is, neck 48 is axially off-set. Thus, when the post 44 is turned, neck 48 will be moved toward or away from neck 60.

Blade 2 is mounted on the posts 44 and 56 by rotating post 44 until necks 48 and 60 are aligned with holes 14 and 16. The blade is then moved so that holes 14 and 16 receive necks 48 and 60. It will be noted that the position of posts 44 and 56 on support plate 36 is such as to permit the blade to be thus dropped over the necks in the unstressed state. Thereafter, with blade 2 in the vicinity of grooves 50 and 62, post 44 is turned in the support plate and neck 48 is thus moved closer to neck 60. This causes the flat bottoms of grooves 50 and 62 to press against said inner rims to force leg 4 toward leg 6. In other words, the free ends of outer legs 4 and 6 are connected to support 36 by a pair of connections which are spaced so as to distort the outer legs toward one another, thus urging the center leg toward a position of relative equilibrium.

At this point, an important feature of the invention is to be noted, namely, that the engagement of the legs 4 and 6 by their respective posts is a pivotal one. That is, the legs are permitted to flex freely, both transverse to the leg and longitudinally of it. That is, each outer leg can twist about an axis which extends in the same approximate direction as the leg. It is this freedom of flexure which permits a new method of operation of the blade and which leads to many of the advantages of the invention, such as ease of calibration, relative non-dependence on critical dimensional tolerances, relative large snap-motion, and the possibility of extreme miniaturization.

Switch support plate 36 is provided at its rear with the up-turned tab 68 (see FIG. 4) which serves to support one end of the actuating arm 70. Referring to FIG. 7, the arm 70 is generally Y-shaped and comprises the leg portion 72 and the two side extensions 74 and 76.

Each of extensions 74 and 76 includes a down-turned tab 78 and 80, respectively. Each extension and a portion of its tab is pierced with one of the slots 82 and 84, as shown. Slots 82 and 84 are large enough to fit freely over necks 48 and 60, respectively. Actuating arm 70 is preferably stamped and formed from metal, but may, if preferred, be molded from moldable plastic such as nylon or Teflon.

As shown in FIGS. 3 and 4, when the arm 70 is mounted in place, the tabs 78 and 80 press, respectively, on the outer edges of the ends of legs 4 and 6 adjacent the mounting holes 14 and 16. The arm 70 is held in this position by the engagement of slots 82 and 84 by necks 48 and 60, and by the end of leg 72 resting on the upper end of tab 68. While the end of leg 72 is shown, for simplicity's sake, as resting on the tab 68, it may be fastened to the tab in pivotal manner by any conventional means. For example, a hole can be provided in the end of leg 72 to receive loosely a screw which in turn threads into the up-standing tab 68; or, the end of tab 68 may be provided with a narrow extension adapted to pass through a hole in the end of leg 72 and be bent over at right angles. Such constructions are not shown in the drawings because they are clearly conventional and well-known in the art.

As has been explained in connection with the description of the blade 2, the forcing of the ends of legs 4 and 6 toward each other will cause the blade to become somewhat "dished," thus displacing the center leg 8 to one side of the element. This "dishing" and displacement are clearly shown in FIG. 3, where the center arm 8 is shown displaced downwardly. Because of the pivotal engagement of the arms by the necks and the resulting pivotal freedom of the outer arms of the blade, these arms are allowed to tilt or twist, and will do so. This tilting or twisting movement is evident in FIG. 3, and in FIGS. 9-12. It will be noted in FIGS. 9 and 10 that the tabs 78 and 80 press against these tilted sides of the legs. If, now, the actuating arm is pressed downwardly (as drawn), the free ends of the outer legs 4 and 6 are rotated about the pivotal engagement of each respective mounting hole rim with its flat-bottomed groove. Such tilting or pivotal action is permitted by the freedom of the outer legs to twist about longitudinal axes. This rotation will cause the blade to "over-center" with a snap-action, thus causing the center leg 8 to move across the plane of instability with a snap action. The final position of the arms 4, 6 and 8 is shown in FIGS. 11 and 12.

Referring more particularly to FIG. 4, there is shown attached to the upper (or inner) end of terminal 30 an L-shaped contact arm 86 with the overhanging end-portion 88. The bottom (as drawn) or inner face of end 88 has attached thereto the facing material 90 of electrical contact metal such as silver, to provide a mating contact surface for contact 18. The end 88 overhangs contact 18 as shown and is positioned to be engaged by the latter in one position of the center leg 8. The attachment of member 86 to terminal 30 is preferably by welding, but may be by soldering, if desired, or brazing.

In like manner, an L-shaped contact arm 92 is fastened, as by welding, soldering or brazing, to the upper (as drawn) or inner end of terminal 28 (see FIGS. 2 and 4). The end portion 94 of arm 92 has a facing material 96 of electrical contact metal such as silver thereon, and the portion 94 with its facing material is positioned to lie underneath the snap-acting blade so that facing 96 will be engaged by contact 20 in one of the positions of center leg 8.

As shown in FIGS. 3 and 4, a casing 100 is provided into which snugly fits the metal ring or flange 22. The top 102 of casing 100 is depressed inwardly, as shown, and a hole 104 is provided at the center thereof which is adapted to receive the flanged guide bushing 106. Guide bushing 106 is provided with a hole 108 which slidably receives the actuating pin 110. A flexible metal diaphragm closure member 112 having a surrounding flange 114 snugly envelopes the upper end of the casing 100.

The center of the diaphragm is provided with a flat portion, and on the outside thereof there is fastened (as by welding) the flat-bottomed actuating button 116. On the underside of the aforesaid flat portion is fastened the flat welding cap 118. (In manufacture, the diaphragm, actuating button and welding cap are assembled, in conventional manner, by a single welding operation.) The flange or rim 114 is soldered or seam-welded to the casing 102 to provide a hermetically sealed closure for the upper end of casing 100. (Of course, the button 116, cap 118, and bushing 106 are all assembled in place prior to such closure operation.)

Pin 110 is inserted in hole 108, and then the switch assembly (all as described earlier) is slid into the casing 100 as shown in FIG. 3. Calibration of the device for pressure and motion response is effectuated by adjusting the longitudinal position of the switch assembly in the casing 100. When the desired position is obtained, the ring 2 is seam-welded (or soldered) to the casing 100, thus providing a hermetic seal at the bottom of the casing.

With this construction, a hermetically sealed switch is obtained in which the casing and mounting parts cooperate to provide adjustment.

In operating, with the device set as shown in FIGS. 3 and 4, if the button 116 is pressed inwardly, the pin 110 will transfer this motion to the actuating arm 70. Depressing of the arm 70 depresses tabs 78 and 80, which in turn exerts a twisting motion or turning moment of the ends of arms 4 and 6, as described above, about their respective fulcrum points, with the result that the center leg 8 will snap upward (as drawn) to bring contact 18 into engagement with facing 90 of contact end 88. Contact end 88 is positioned close enough to contact 18 so that center arm 8 cannot reach an upper equilibrium position. Thus, upon release of the actuating button 116, diaphragm 112 moves button 116 upward and the pin 110 and arm 72 are released. The outer legs 4 and 6 pivot back toward their initial positions and the center leg 8 snaps back into the FIG. 3 position. For clarity as to the resulting motions, reference is directed to FIGS. 9 and 10 which show the center leg 8 in one position (contact 20 engaging facing material 96), and FIGS. 11 and 12 show the center leg in the upper or "snapped-over" position (contact 18 engaging facing material 90).

If desired, the end of leg 72 may be pivotally fastened to the tab 68, and either (but not both) of tabs 78 and 80 may be eliminated. Assuming, as an example, that tab 80 is not used and that tab 78 continues to bear against the outer edge of the end of leg 4, motion of the actuating arm 70 will serve to impart a twisting motion to leg 4 which will in turn cause the center leg to snap.

Referring now to FIGS. 13 and 14, there is shown another embodiment of the invention. In this embodiment of the invention the same principle of operation of the snap-acting blade is used, i.e., a mounting therefor which permits a rotation of the ends of the outer arms, but differs as to where the fulcrum lies.

As in the previous embodiment, the ring 22, glass header 24, and terminals 26, 28, and 30 are provided. The shoulder 32, neck 34, and switch support plate 36 are also provided. The upper contact arm 86, lower contact arm 92 are likewise provided and are attached, as before, to their respective terminals 30 and 28.

In this instance, however, the snap-acting element 120 is mounted by the outside edges 122 and 124 of the side arms 126 and 128. The mounting is accomplished in the mounting bar 130 which lies across the support plate 36 at one end thereof and is attached thereto as by welding. Bar 130 is of metal and has attached at each end thereof the upturned legs 132 and 134. Each of legs 132 and 134 has formed across its inside face the V-groove 136 and 138, respectively. The outer edge of the end of each side arm is provided with a flat-bottomed notch 140 and 142, respectively, each of which notches straddles its respective mounting leg 132 and 134 to pre-

vent longitudinal motion of the snap-element. When mounted, the flat bottoms 144 and 146 of the said notches engage the V-grooves 136 and 138, respectively. It will be noted that the notches 140 and 142 may be so deep, if desired, that portions of the edges of ends 122 and 124 may extend laterally beyond the support legs 132 and 134. In such a construction, the blade may then be actuated by pushing on these outer edge portions (as in the previous embodiment) or on the inside (as in this embodiment).

An actuating bar 148 is provided having at one end thereof the down-turned tabs or legs 150 and 152. Each of these legs is chamfered to a knife-edge, and, as can be clearly seen in FIG. 14, bears against the outer legs 126 and 128 but adjacent the inner edges thereof. A clevis 154 is provided at this end of the bar 148 to provide electrical clearance between bar 148 and contact arm 86, if necessary, when the arm is depressed.

The other end 156 of arm 148 rests on top of an upturned leg 158 which is attached to support plate 36. The leg or tab 158 is made wider in this instance, than in the previous embodiment, and a pair of pins 160 and 162 pass through suitable holes in end 156 and into leg 158, these pins serving to keep the end 156 of the arm from sliding or swinging horizontally on leg 158, and thus serve to orient the actuating arm with respect to legs 126 and 128 of the snap-acting element. The fit of pins 160 and 162 in their respective holes is such as to permit the arm to rock slightly about leg 158.

A center leg 164 is provided for blade 120 (corresponding to center leg 8 of blade 2) and is provided at its end with contacts 166 and 168, which correspond to contacts 18 and 20.

A push pin 110 is provided, as in the previous embodiment, and bears against the actuating arm 148 as shown.

This second embodiment is fastened in a casing alike in all respects to the previous casing 100, thus providing a hermetically sealed enclosure for the switch parts.

In operation, and referring to the parts positioned as shown in FIG. 14, when the pin 110 is pushed downwardly, arm 148 is depressed, which in turn causes legs or tabs 150—152 to depress the inner edge of side arms 126 and 128 about the fulcrum points provided by V-grooves 136 and 138. This rotation about the fulcrum points will cause the center leg 164 to snap downwardly, as drawn, and cause contact 168 to engage contact arm 92—94 while opening the electrical connection between contact 166 and contact arm 88. Release of push pin 110 will permit the reverse motion of the parts.

It is to be noted that the initial bowing of the outer legs 126 and 128 inwardly toward each other is accomplished, in this instance, by mechanically bending the side legs 132—134 toward each other.

It is to be noted that there is a difference between the operation of the FIG. 1-12 embodiment, and that of FIG. 13-14, in regard to the relationship between the motion of the actuating arm in each case and the center leg. In the FIG. 1-12 embodiment, the actuating arm moves in a direction opposite to the eventual snap-motion of the center leg; whereas in the FIG. 13-14 embodiment, the motion of the actuating arm is the same as the snap-motion of the center leg. The arrangement of the FIG. 1-12 embodiment will be found to be advantageous in situations where the switch is subject to vibrations. There will be less tendency for vibrations to affect the stability of the FIG. 1-12 embodiment than will be the case for the FIG. 13-14 embodiment.

In view of the above, it will be seen that the several objects of the invention are achieved and other advantageous results attained.

In the embodiment of the invention illustrated in FIG. 15, blade 2 has its outer leg 6 pivotally connected to support 36 by the edge of hole 16 engaging the chamfered recess 62, as in the embodiment of FIGS. 1-12. The free end of outer leg 4 is fixed in position relative to

support 36 by being secured to the upper end of a metal post 180 by welding or soldering or by riveting, as shown. Thus a portion of post 180 of reduced diameter passes through hole 14 and its upper end is upset or deformed to form rivet head 181. Rivet 181 clamps the end of leg 4 to the upper surface of the post and the post is fixed to the support 36. The spacing between recess 62 of post 56 and the body of rivet 181 is selected so that the legs 4 and 6 are deformed toward one another and center leg 8 is urged toward a downward equilibrium position so that contact 20 engages contact surface 96. By means of an electrical connection to post 180, the embodiment of the invention shown in FIG. 15 features improved electrical contact to the blade 2.

To actuate the snap-acting device just described, an actuator rod 182 is slidably supported in a guide 183. It has a control button 184 at its upper end and its lower end 185 is positioned to engage an outer, upper surface portion of outer leg 6. Thus, by depressing button 184, leg 6 is pivoted and in a snap-action, center leg 8 is carried away from the position shown in FIG. 15 and contact button engages contact surface 99. With member 88 positioned as shown, when control button is released, the blade 2 returns to its initial condition in a snap action.

Of course, actuation of the blade in the embodiments of FIGS. 1-12 and 13-14 can be accomplished by producing pivotal movement of only a single leg. An actuator of the general type illustrated in FIG. 15 may be employed.

As explained in connection with the embodiment of FIGS. 1-12, contact 88 is positioned so that only a single equilibrium state (downward) is provided for center leg 8 and this is also shown in FIG. 15. The same result can be achieved by constructing post 180 with its upper surface at an appropriate angle, such as represented by broken line 186. While the angle illustrated provides a single equilibrium state in a downward direction, an opposite angle will obviously effect a single upper equilibrium state.

Obviously, in any of the embodiments of the invention which have been illustrated and described, the upper and lower contacts may be appropriately positioned so that the center leg 8 is urged toward upper and lower equilibrium positions. For such applications, means are provided for actuating the blade from each position whereupon it goes into the other position with a snap action. For example in FIG. 15, upper contact 88 may be raised and an actuator assembly like the one designated by numerals 182-185 is positioned below leg 6 to effect pivotal movement in the opposite direction.

As many changes could be made in the above constructions without departing from the scope of the invention, it is intended that all matter contained in the above description or shown in the accompanying drawings shall be interpreted as illustrative and not in a limiting sense.

What is claimed is:

1. A snap-acting mechanism comprising a support, a resilient normally flat blade having spaced-apart outer legs and a center leg joined thereto by one end and extending therebetween, means attaching said outer legs to said support including a pair of upright posts for said outer legs, one of said posts being provided with a groove therein and the end of a corresponding one of said outer legs having an edge engaging said groove in pivotal connection therewith, the other of said posts constraining movement of the remaining outer leg in a direction away from said one post, said one post being movable at least in part in said direction toward an adjustably-fixed position wherein said posts are spaced apart a distance such as to distort the blade and thereby cause said center leg to snap across a position of unstable equilibrium, and actuating means adapted to engage said blade and impart pivotal movement to the end of said one outer leg.

2. A snap-acting mechanism according to claim 1 in

which said other post has a groove therein and the end of the corresponding outer leg has an edge engaging said groove in said other post in pivotal connection therewith.

3. A snap-acting mechanism according to claim 1 in which the end of said other outer leg is secured at an angle relative to a line extending between said ends of said outer legs.

4. A snap-acting mechanism according to claim 1 further comprising an electrical contact carried by the free end of said center leg and another electrical contact mounted on said support for engagement with said first-mentioned contact, and means for completing electrical circuit connections to said contacts.

5. The snap-acting mechanism of claim 1 in which said actuating means comprises an elongated member having a leg portion and side extensions having means thereon adapted to engage each of the said outer legs to twist said outer legs about an axis.

6. The snap-acting mechanism of claim 1 in which said actuating means comprises an elongated member having a center leg and side extensions attached thereto, each of said side extensions having at its end a tab at an angle thereto, each tab engaging one of said ends near the edge thereof and being adapted to move said edge pivotally about the respective support.

7. A snap-acting mechanism comprising a support, a resilient normally flat blade having spaced-apart outer legs and a center leg joined thereto by one end and extending therebetween, means for attaching said blade to said support comprising a pair of spaced-apart posts, the ends of said outer legs being provided with holes adapted to fit loosely over said posts, each of said posts being provided with a groove receiving therein a portion of the rim of the respective hole, one of said posts being movable at least in part toward the other of said posts to an adjustably fixed position wherein said posts are spaced apart a distance such as to strain said outer legs abnormally toward each other to distort said blade into a dished shape, a third support post, and an actuating arm for snapping said blade, said arm comprising an elongated center leg and two side extensions attached to one end thereof, each of said side extensions having a hole at its other end and a tab beyond said hole, each tab extending outwardly therefrom at an angle and thereto, said holes fitting over said posts and said tabs bearing against the outer edges of said actuating arm resting on said third support.

8. A snap-acting mechanism comprising a support, a resilient normally flat blade having spaced-apart outer legs and a center leg joined thereto by one end and extending therebetween, means for attaching said blade to said support comprising a pair of spaced-apart posts, the outer edges of the ends of said outer legs being provided with notched portions, each of said posts on its inner side being provided with a transverse groove receiving therein said notched portions, one of said posts being movable at least in part toward the other of said posts to an adjustably fixed position wherein said posts are spaced apart a distance such as to strain said outer legs abnormally toward each other to distort said blade into a dished shape, a third support post, and an actuating arm for snapping said blade, said arm comprising an elongated center leg and two side extension legs attached to one end thereof, each of said side extensions having at its end thereof a tab extending outwardly therefrom at an angle thereto, said tabs engaging the ends of said outer legs adjacent the inner edges thereof, and means holding and guiding the other end of said actuating arm on said third support.

9. A snap-acting mechanism comprising a support, a resilient normally flat blade having spaced-apart outer legs and a center leg joined thereto by one end and extending therebetween, said support including a pair of upright posts, each post comprising a body portion and a neck portion of reduced diameter, each of said outer legs being provided with a hole adjacent its end and fitting loosely

over one of said neck portions, one of said posts being stationary and the other of said posts being movable toward and adjustably fixed position to bring its neck portion toward and away from the other neck portion, said movable post being positionable to strain said outer legs toward one another to dish said blade, and actuating means for engaging an end portion of one of said outer legs to tilt said end portion on the corresponding neck portion.

10. The snap-acting mechanism of claim 9 in which said other post is provided with another neck portion of reduced diameter, one of said neck portions being engaged by and rotatable in said support, the other of said neck portions being engaged by the rim of one of said holes,

and one of said neck portions being axially eccentric relative to said other post whereby rotation of said other post in said support causes said other neck portion to move laterally with respect to said support.
